PADDLE WHEEL BOAT

Dale E. Love, Holland, Mich., assignor to
Lovecraft Boat Company, Holland, Mich.

Filed May 20, 1970, Ser. No. 23,071

Term of patent 14 years

Int. Cl. D12—06

U.S. Cl. D71—1

FIG. 1

FIG. 2

FIG. 3

FIG. 5

FIG. 6

FIG. 4

FIG. 1 is a perspective view showing lateral and front-al features of a boat embodying the design;

FIG. 2 is a perspective view showing lateral and rear features of the boat shown in FIG. 1;

FIG. 3 is a front perspective view of the boat of FIGS. 1-3;

FIG. 4 is a rear perspective view of the boat of FIGS. 1-3;

FIG. 5 is a perspective view similar to FIG. 1 but showing the top in a folded and reclining positions; and

FIG. 6 is a perspective view similar to FIG. 2 but showing another embodiment of the design in which there is no top.

I claim:

The ornamental design for a paddle wheel boat, substantially as shown and described.
